FLAG DISPLAY CABINET IN WHICH THE
FLAG IS HELD ON A ROLLER

Oscar R. Glass, Cincinnati, Ohio; Margaret C. Glass, administratrix of said Oscar R. Glass, deceased, assignor to Oscar R. Glass, Jr., Cincinnati, Ohio

Application July 19, 1945, Serial No. 605,944

4 Claims. (Cl. 40—82)

1

My invention relates to cabinet structures used in the preservation and display of the flag. They are for use both indoors and out of doors, and in their various forms follow one line of construction which results in safety of the flag itself, and simplicity in handling. In addition, as an objective of my invention is the illumination of the flag, to which end provision is made for light not only to reflect on the flag but to shine through the flag from the reverse side to that which is exposed.

It is an object to provide a cabinet or box which can be hung on the wall or on a pillar in which box or cabinet the flag is held in a roller and so arranged with a mounting strip that the whole flag is exposed when unwrapped from the roller and extended. It is an object to provide for availability of the interior of the cabinet for installing and removing the flag mounting roller. This is accomplished by arranging that the side of the box facing the observer is hinged at the line of its engagement with the top of the box. It is also an object to provide for closing the box entirely while at the same time permitting ready extending of the flag and this is accomplished by making the bottom of the cabinet removable, same having a sliding joint with the end walls of the box.

In order to illuminate the flag, advantage is taken of the fact that the whole bottom of the cabinet is open when the flag is in use, the convenient thing being to simply place the bottom of the cabinet on the top of the cabinet after its removal. Thus the interior of the box may be and is preferably formed with a white reflective surface while the flag roller is mounted so that it is in a position intermediate of the open bottom of the cabinet. A source of illumination which may be a gas filled tube, for example, is mounted in the cabinet, but is concealed by the dropping of the hinged front wall to its normal position. The light from this tube shines down on both faces of the flag and illuminates it very much more beautifully than if the light were merely reflected against it. In some constructions a pair of gaseous tube lamps are used in the lighting unit, spaced so as to be on each side of the vertical plane of the flag roller mounting. Even with the twin tube arrangement, it is desirable to have a light reflective surface on the interior of the box.

In order to illustrate my invention, several examples have been selected.

Figure 1 is a view of one form of device when closed.

Figure 2 is a view of the same cabinet but with the front wall swung upwardly on its hinge, showing the flag mounting and the slideway construction of the bottom panel.

Figure 2a is a detail view of the bottom panel of the cabinet of Figure 2.

Figure 3 is a front elevation, but with the flag extended.

2

Figure 4 is a view of a modification in which the cabinet is illuminated.

Figure 5 is a like view showing the front wall hinged up and the flag roller plus the illumination source, as well as the mounting of the bottom panel.

Figure 5a is a detail view of the bottom panel of the cabinet of Figure 5.

Figure 6 is a like view showing the flag extended with the device in use.

Referring first to Figure 1, the cabinet, slightly longer than the flag to be used is wide, is arranged with fixed end panels 1, 2 and a fixed top 3. Hinged to a rib 3a at the front of the fixed top by hinges 4, is a front side wall panel 5 which has latches 6 to hold it down in place, preferably engaging over pins in the end of side wall 5, in proper location as indicated. The rear side panel 5a is fixed.

The end walls are notched at 7, 7 and the hinged front panel has a rib 8 along its base which engages in said notches. The end walls have a pair of spaced strips 9, at each side near their lower end which form a slideway for the bottom panel of the cabinet. The panel in this form is a thin strip of material 10 with a rib 11 for strength and for grasping it in the fingers. It slides into place when the front panel is hinged upwardly as shown in Figure 2. The location of the slideway is such that the bottom panel lies just above the undercut portions of the end walls so that the rib 8 engages underneath the said bottom panel when the front wall is closed down.

The cabinet thus made is of light weight construction. Within the cabinet located on the end walls are two brackets 12, providing sockets for the tips 13 of the roller 14, around which the flag 15 is wound when not in use.

When it is desired to extend the flag the front wall is unlatched and lifted up, the slide bottom removed, the flag pulled down, the bottom piece laid on the top of the cabinet and the front hinged down and latched again. In order to cause the flag to be entirely extended, a strip of fabric 16 is mounted upon it and attached to the roller. The strip is tacked to the roller so that when the flag is entirely unwound and extended, the strip will lie within the cabinet and the flag alone be extended fully from the bottom of the cabinet.

When closed up the cabinet is relatively weather-proof and preserves the flag against wetting or becoming soiled so that it constitutes an excellent storage and can be left on a porch, for example, without ruining the flag. To roll up the flag the front of the cabinet is raised, the roller removed, the flag wound on it and replaced, the bottom wall of the cabinet slid into place and the front wall closed. It is not required that the

roller be a spring roller although, of course, it could be.

Referring to the device shown in Figures 4, 5, and 6, the cabinet is formed with fixed end walls 20 and 21, a fixed top wall 22, and a hinged front wall 24. In this instance mounted near the base of the end walls on the inside are guide strips 25, one at each end. The sliding bottom 26 in this instance, when in place, extends under the end walls and fits snugly against the back wall or rear panel 24a.

The portion of this bottom panel intermediate the end walls is raised by the portion 27, which leaves projecting ends to underlie the end walls, and near the ends of this raised portion 27 are mounted guide strips 28. The strips 25 on the end walls act as a guideway being engaged by the raised portion 27 and the strips 28 at each end of the cabinet. Thus the bottom is removable as in the first instance. The front panel in this case comes down into engagement with the front edge of the bottom thus locking the bottom in place when it is closed.

Located on the end walls, as in the first instance are the brackets 29, forming sockets for the tips of the roller 30 on which is the flag 31.

The interior of the box is covered with reflective material. It may be white enamel in a number of coats, but in the de luxe style of cabinet it is formed of applied sheets of white plastic veneer. Located in the top of the box above the roller is a lighting unit consisting of luminous vapor tubes 32, with connections and mountings as shown, but which will not be described in detail. Other upwardly located sources of light will serve, but the vapor tubes are not productive of much heat and are preferred, because special ventilation is not required. The tubes are preferably a pair, arranged parallel with each other and so spaced and located that the location of the roller mountings lies in a vertical plane of the intervening space. One tube could be used, of course, with the reflective inner walls spreading the light.

As a result, as already indicated, when the bottom is removed, the flag extended and the front of the box closed down and the lights turned on, the effect of the reflective interior of the cabinet from the middle of the open bottom of which the flag extends, and particularly where there are two spaced tubular lights, the flag is illuminated from both sides and in addition has room to flutter in the breeze, if any, giving a very brilliant and beautiful effect.

As in the first instance when the flag is rolled up and the cabinet closed, the flag is well protected. As in the first case arrangements of attachment to the roller are such that the flag will be fully extended when the roller is unwound.

A white plastic panel 40 may be loosely slid into the cabinet above the luminous tubes.

Normally it is not necessary to form a hole in the cabinet for the electric cord to connect up the device to a source of current since the bottom of the cabinet is open when in use. However, with the fixedly installed system, it will be feasible to provide connections to a fitting (not shown) similar to a wall outlet fitting, into which the prong of an electrical cord can be inserted. Thus there need not be a hole extending through the box.

It will be noted that in each of my constructions there is the common cabinet features in several forms, and of course, other forms are

feasible. In any of the cases the cabinet can readily be locked. Thus in the modification shown there is a small hasp 41, which engages over a loop plate 42 on the bottom panel, thus providing for a small padlock to lock the entire structure closed.

Such a hasp and loop could also be used with the other constructions in all of which the front wall must be elevated before the interior of the box is available.

Having thus described my invention, what I claim as new and desire to secure by Letters Patent is:

1. A cabinet for housing of a flag, and adapted for the extension of said flag for display which comprises a cabinet fixedly closed at the ends, top and rear panel portions, and having a hinged front panel, a bottom for the cabinet which slidably engages with the end walls and closes the cabinet when not used for display, and means within the cabinet for mounting the ends of a roller lengthwise thereof, in position for a flag about said roller to be projected through the bottom of the cabinet when the bottom is removed.

2. The combination of claim 1 in which the interior of the box is surfaced with light reflective material, and a source of illumination is housed therein, the mounting for the roller being located between the front and rear edges of the end walls so that light reflected from the interior of the cabinet will impinge on both sides of the flag.

3. A cabinet for housing a flag comprising end walls, a top wall, and a back wall fixedly secured together and slightly longer than the flag to be displayed is wide, a front wall closing the cabinet at the front and hingedly connected to the top wall thereof, a bottom panel, and slideway means located on the ends of the bottom panel, and on the lower edges of the end walls for slidably mounting the bottom panel removably in place to close the cabinet from the bottom, and brackets located in the interior of the end walls approximately midway of their extent so as to mount a flag wound roller rotatably therein, with the flag, when the bottom of the cabinet is removed, extending midway approximately of the open bottom of the cabinet for display purposes.

4. The combination of claim 3 in which the front wall engages the front edge of the bottom wall, hence when closed with the bottom in place, constituting the sole means of access to the cabinet.
